DESIGN FOR A DOLL OR SIMILAR ARTICLE

Eleanor Shannahan, Easton, Md.

Application March 11, 1936, Serial No. 61,572

Term of patent 7 years

To all whom it may concern:

Be it known that I, Eleanor Shannahan, a citizen of the United States and a resident of Easton, county of Talbot, and State of Maryland, have invented a new, original, and ornamental Design for a Doll or Similar Article, of which the following is a specification, reference being had to the accompanying drawing, forming part thereof.

Figure 1 is a front view of a doll showing my new design;

Figure 2 is an edge view of the doll shown in Figure 1.

The dominant features of the design consist in the provision of a slouch hat, large in comparison to the head of the doll, and a curved formation simulating arms with the hands arranged in the pockets of the garment with the hat, arms formation and garment presenting different colored effects.

I claim:

The ornamental design for a doll or similar article as shown and described.

ELEANOR SHANNAHAN.
